UNITED STATES PATENT OFFICE.

ABRAHAM GOLDMAN, OF NEW YORK, N. Y.

SHOE-POLISHING DEVICE.

Application filed March 16, 1922. Serial No. 544,312.

To all whom it may concern:

Be it known that I, ABRAHAM GOLDMAN, a citizen of the United States of America, residing at New York, in the county of New 5 York and State of New York, have invented new and useful Improvements in Shoe-Polishing Devices, of which the following is a specification.

In carrying out the present invention it is 10 my purpose to provide a shoe polishing device wherein the polishing element will be power driven so that the shoes may be polished conveniently and quickly and without the use of the usual hand cloths that are now 15 generally used.

It is also my purpose to provide a motor driven shoe polishing device which will embrace the desired features of simplicity, efficiency and durability, which may be conveniently manipulated by the operator and wherein the component parts will be so arranged and correlated as to reduce the possibility of derangement to a minimum.

With the above recited objects in view, 25 and others of a like nature, my invention resides in the construction, combination and arrangement of parts set forth in and falling within the scope of the appended claim.

In the accompanying drawings: 30 Figure 1 is a side elevation of a motor driven shoe polishing device constructed in accordance with the present invention.

Figure 2 is a vertical sectional view, the parts being shown in elevation.

Figure 3 is an end view of the same.

Figure 4 is a sectional view on the line 4—4 of Figure 2.

Figure 5 is a like view on the line 5—5 of Figure 2.

Referring now to the drawings in detail 40 1 designates a spindle which is designed to remain stationary. Pinned or otherwise secured to one end of the spindle 1 is a hub 2 provided with an outwardly projecting circular flange 3, and riveted or otherwise secured to the flange 3 is a circular plate 4. Fixed to the other end of the spindle 1 is a handle 5 adapted to be grasped in the hand of the operator.

Arranged concentrically of the spindle 1 50 is a drum 6. In the present instance one end of the drum 6 is arranged in juxtaposition to the periphery of the plate 4, and disposed concentrically of such plate, while the other end of the drum 6 is equipped with an inwardly extending flange 7 that

surrounds the spindle 1 adjacent to the spindle end of the handle 5. The central portion of the flange 7 is fixed to a hub 8 arranged concentrically of the spindle 1 adjacent to the handle and adapted for rotation about such spindle. Surrounding the drum 6 and appropriately secured thereto is a covering of polishing material 9 which may be formed of any suitable substance. 60 65

Arranged concentrically of the spindle 1 between the hubs 2 and 8 is a sleeve 10, and surrounding the sleeve 10 is a convoluted main spring 11, the inner convolution of which is fastened to the sleeve. Encircling 70 the spring 11 is a casing 12 and the outer convolution of the spring 11 is fastened to this casing 12, as clearly shown in Figure 2 of the drawings, so that in the operation of the spring after the latter has been wound up motion may be imparted to the casing 12 to revolve the latter. Surrounding the spindle 1 adjacent to the hub 2 is a disk 13 that is integral with the adjoining end 75 of the spindle 1. This disk 13 is fastened to the plate 4 by means of screws 14 or other appropriate securing devices, so that the disk 13 will remain stationary with the plate 4 in the rotation of the casing 12. Arranged 80 concentrically of the casing 12 is a second casing 15 having an outer cylindrical wall and having one end wall arranged in juxtaposition to the periphery of the disk 13 and overlying the flange 16 formed on the disk 13 and the other end formed with an end plate 17 that surrounds the spindle 1 adjacent to the hub 8. 85 90

Arranged concentrically of the spindle 1 is a driving gear 18 that is rigidly secured to the spring casing 12 and meshes with a 95 pinion 19 fixed to the inner end of a stub shaft 20 journaled in a bearing formed in the end of plate 17 adjacent to the outer circular wall of the casing 15. The outer end of the stub shaft carries a pinion 21 that 100 meshes with a gear 22 fixed to the hub 8.

By means of this construction it will be seen that when the spring 11 unwinds motion will be transmitted to the casing 12, thence through the driving gear 18, pinion 19, stub shaft 20, pinion 21 and gear 22 to the hub 8, thereby rotating the drum 6 carrying the polishing material, so that the shoe engaged by the polishing material may be polished. 105 110

In order to wind the spring 11 suitable mechanism may be employed. In the pres-

ent instance a gear 23 surrounds the sleeve 10 and is fixed thereto and meshes with a pinion 24 fixed upon a stub shaft 25 journaled in the disk 13. The outer end of the 5 stub shaft 25 projects through the end plate 4 and is provided with a key 26, whereby the pinion 24 and gear 23 may be operated to revolve the sleeve 10 and thereby wind up the spring 11. In order to prevent 10 retrograde movement of the winding shaft 25, such shaft is equipped with a ratchet wheel 27 that is engaged by a spring pressed dog 28 pivoted upon the outer side of the disk 13, as clearly illustrated in Figure 4 15 of the drawings.

To hold the drum 6 against rotation under the action of the spring 11 until it is desired to use my improved polishing device, I provide a lever 29 that is pivoted 20 between ears 30 formed on the handle 5 adjacent to the flange 7. The flanged end of the lever 29 is formed with a holding dog 31 adapted to engage a stop member 32 25 formed on the flange 7, while the other end of the lever 29 is engaged by the inner end of a spring 33, the other end of which is seated in a depression formed in the handle 5 adjacent to the outer end of the latter, as 30 illustrated in Figure 2 of the drawings. 35 By means of this construction it will be seen that when the handle is grasped and the lever 29 depressed against the action of the spring 33 the dog 31 will be moved out of the path of movement of the stop member 32, thereby permitting the drum 6 on the flange 7 to be revolved under the action of the main spring 11.

In the present form of my invention I have fastened to the outer side of the plate 40 4 a plate 34 arranged at the center of the disk, and suitably secured to this plate 34 is a rod 35 arranged in axial alignment with the spindle 1 and the outer end of this rod 35 is equipped with a dauber 36, by means 45 of which the polishing material may be applied to the shoes.

In the present instance the polishing material 9 is carried by an open-ended cylinder 37 that surrounds the drum 6 and is 50 frictionally held thereto. This open-ended cylinder 37 carrying the polishing material may be removed from the drum whenever it is necessary to replace the polishing material.

From the foregoing description, taken 55 in connection with the accompanying drawings, the construction and mode of operation of my improved polishing device will be readily understood by those skilled in the art to which my invention appertains, and it 60 will be seen that I have provided a power operated polishing device wherein the spring motor may be wound up whenever necessary, and subsequently released when desired, so as to revolve the polishing element in order to bring about the polishing 65 of the shoe.

While I have herein shown and described one preferred form of my invention by way of illustration, I wish it to be understood 70 that I do not limit or confine myself to the precise details of construction herein shown and described, as modifications and variations may be made within the scope of the claim and without departing from the 75 spirit of my invention.

I claim:

A shoe polisher including a spindle, a handle mounted on one end of the spindle, a circular plate mounted on the other end 80 thereof, a sleeve member rotatable on the spindle and of a length less than the spindle, a tubular drum having an end wall at one end thereof formed with a spindle receiving sleeve for rotatably mounting said 85 drum on the spindle, the other end extending over the periphery of the circular plate, a casing mounted on the circular plate within the drum, a spring housing rotatable on the sleeve member within the casing, a coiled 90 spring in said housing having one end secured to said sleeve member and the other end to said spring housing, gears carried by said spring housing and drum sleeve, gear 95 connections rotatable in said casing and meshing with said gears for transmitting the rotary movement of the spring housing to said drum, a winding mechanism mounted on said casing and cooperating with the sleeve for winding the spring and holding 100 it in tensioned position, polishing material mounted on the periphery of the drum, and means mounted on the handle for controlling the rotation of the drum.

In testimony whereof I affix my signature. 105

ABRAHAM GOLDMAN.
